FOLDING GATE

Filed July 3, 1931

UNITED STATES PATENT OFFICE

MICHAEL MARTINEK, OF LYONS, ILLINOIS, ASSIGNOR TO WESTERN WIRE & IRON WORKS, INC., OF CHICAGO, ILLINOIS, A CORPORATION OF ILLINOIS

FOLDING GATE

Application filed July 3, 1931. Serial No. 548,625.

This invention relates to folding gates, and its primary object is to provide a new and improved folding gate which is provided with strengthening means to assure rigidity and ease of operation of the gate and, at the same time eliminate all side-sway in the gate when extended and which is movable with the gate during the folding and extending movement of the gate.

10 A further object of the invention is to provide a folding gate which is arranged in a pocket, and which is provided with means for adjustably fixing the gate in the pocket.

15 A still further object is to provide a gate which has a frame which is provided with means cooperating therewith for adjustably securing the frame in the pocket; which has a reinforcing member arranged in the top thereof to prevent side-sway of the gate; which has a reinforcing member hinged at the top thereof for engagement and cooperation with an adjoining gate, which has a track foldable outwardly when in use and upwardly against the frame when not in use.

20 Numerous other objects and advantages will be apparent throughout the progress of the following specification.

25 The accompanying drawing illustrates a selected embodiment of the invention and the views therein are as follows:

Fig. 1 is a detail elevation partly in section showing the manner in which the improved gate may be arranged in a pocket concealed in a wall.

30 Fig. 2 is a vertical sectional view on the line 2—2 of Fig. 1.

Fig. 3 is a view similar to Fig. 1 showing gate in collapsed position.

35 Fig. 4 is a detail elevation partly in section showing the top support, and interlocking connection between cooperating gates.

Fig. 5 is a detail sectional view on the line 5—5 of Fig. 4.

40 Fig. 6 is a detail plan section showing the gate in folded position in the pocket.

45 Referring to the drawing, 10 designates a wall, jamb, partition, or other surface which may be provided with a pocket 11 into which a metal frame 12 may be arranged.

50 The frame 12 may comprise an end mem-

ber 13 and upper and lower members 14 and 15 respectively. These latter members are preferably made of channel bars connected together at their corners in any desirable manner, such as by welding.

55 A gate 16 comprising a plurality of spaced vertical bars 17 having flat bars 18 pivoted thereto as indicated at 19 to provide the conventional diamond lattice type of folding gate.

60 Some of the vertical bars 17 are provided with rollers 20 which are adapted to roll in a channel-shaped track 21 which is pivotally connected to the lower channel frame member 15 as indicated at 22. This bottom track may be folded down into the position shown in Fig. 1 to permit the gate to roll therein and may be folded up in the position shown in Fig. 3 when the gate is in collapsed position. The gate, when folded, is adapted to 65 fold up into the frame and extend into the pocket 11 and be concealed from view when not in use, there being frame stiffening members 23 connected to the upper and lower members 14 and 15 and to the end bar 24 70 which may be reinforced by a channel member 25. Thus, the gate is securely held in position in the frame 12, permitting all the bars 17 and the cooperating diamond lattice members to be pulled outwardly from the 75 pocket on the frame but holding the end bar 24 rigidly to the supporting frame 12.

78 The frame 12 with the folding gate fixed thereto is set in the pocket 11 as a unit, there being a fixed member 26 arranged in the back 85 of the pocket by which, members such as nuts 27, are carried. These nuts receive upper and lower screw members 28 which pass through aligned openings in lugs 29 which are fixed to the upper and lower frame members 14 and 15. A collar 30 is fixed to each screw member 28 and is arranged between a pair of lugs 29 so that when the screw members are threadedly engaging the nuts 27, the frame and its cooperating gate may be 90 adjusted to proper position.

95 The vertical bars 17 may have a fitting 31 fixed to the top thereof, which fitting is provided with a horizontal slot 32 through which a flexible relatively wide steel tape 33 passes.

- The end of the steel tape is bent over and fixed to the outer vertical bar 17 as indicated at 34, Fig. 5, and is threaded through the vertical bars as clearly shown in the drawing. Some of the outer vertical bars 17 may be provided with an additional member 35 having relatively wide upper slots 36 for receiving a jointed bar 37, the joint being indicated at 38, Fig. 1. The jointed bar 37 has its one end fixed to the member 35 as indicated at 39, permitting that part of the bar, to the right of the pivot 38, to fall downwardly in the position shown in Fig. 3 when the gate is collapsed. This bar is adapted to pass through similarly shaped openings provided in fittings 35' fixed to the vertical bars 17' of an adjacent or adjoining gate when the second gate is adapted to abut thereagainst. This bar connects therebetween. The steel tape 33 provides a reinforcing member at the top of the gate and as this reinforcing member is fixed to the end vertical bar but slidably mounted with reference to the other bars, the tape is free to move inwardly and outwardly from the pocket 11. A track or guide 40 is arranged in the upper corner of the frame 12 and guides the tape when the gate is moved to collapsed position. A handle 41 may be fixed to the outer end bar 17 but has horizontal slidable movement therein to permit the grip portion 42 of the handle to lie relatively flush with the outside of the end bar. In operation, the folding gate is arranged in position in the frame 12, the end member 24 being fixed to the frame. The bolts 28 are arranged in place and the entire frame and its cooperating gate is inserted in the pocket in a wall. The bolts 28 are adapted to engage the nuts 27 thereby permitting the frame to be supported in position, the bottom lugs 29 engaging the floor of the pocket and holding the frame the required distance from the floor. The bolts 28 may thus be operated to bring the frame and gate to proper position inside of the pocket. The lower track 21 is then moved from the position shown in Fig. 2 to the position shown in Fig. 1, thus making a lower track in which the gate operates. When the gate is pulled outwardly from the position shown in Fig. 3 to the position shown in Fig. 1, the first bar 17 to which the reinforcing member 33 is attached, pulls the reinforcing member outwardly as the fittings 31 on the bars slide along. When the gate is in extended position, the reinforcing member 31 will be in the position shown in Fig. 1. When the gate has reached substantially the end of its outward travel, the outer end of bar 37 is swung upwardly on its pivot 38 until it is in alinement with a slot provided in the fitting 35' of an adjacent gate. This construction makes a rigid connection be-

tween adjacent gates and also rigidly supports the gate when in extended position. When the gate is closed and brought to collapsed position, the outer end bar 17 is merely pushed inwardly. This inward movement causes the vertical bars to come closer together and slides the reinforcing member inwardly. As the gate is being collapsed, the corner member or track 40 engages the outer edge of the reinforcing member 33 and causes it to extend downwardly into the pocket as shown in Fig. 3. When a gate is applied to a relatively large opening, it may be made in two sections, one on each side of the opening. After one section is closed, the bar 37 will slide out of the co-operating section and then would be down in the position shown in Fig. 3. After one entire section has been closed, the track is then raised upwardly as shown in Fig. 3 and locked in position by means of a pivoted latch 43. Where more than one section is employed, the other section is collapsed in the same manner, it being understood, however, that only one bar 37 is required for adjacent sections. The entire gate may be folded in the pocket and if desired, a hinged plate 44 may be provided for closing the pocket as shown in Fig. 6.

The invention provides a folding gate having a reinforcing member which eliminates all side-sway when the gate is in extended position. The improved gate further is provided with means for providing an additional reinforcement for engagement with an adjacent gate. Means are provided for connecting the gate to a fixed frame which may be inserted in a pocket or recess provided in the wall. The screw members hold the frame in position in the pocket and permit adjustment to "true up" the gate and make it operate properly. The folding track provides a rigid base support and is easily and quickly moved out of position when not in use. The folding track, in combination with the reinforcing member, and the foldable bar provides rigid reinforcement for the gate preventing it from swaying inwardly or bulging, a condition which is prevalent in conventional gates, particularly in gates for wide openings.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

1. The combination of a wall having a pocket therein, a frame removably inserted in said pocket, complementary screw members arranged in said pocket and on said

- frame and engageable with each other for holding the frame in the pocket, a folding gate operatively connected to said frame and adapted to be foldingly received in said pocket,
- 5 et, a bottom track pivotally connected to said frame and adapted to be swung upwardly across the opening in the pocket when the gate is in folded position, and a hinged plate for closing the opening to said pocket.
- 10 2. The combination of a wall having a pocket therein, a frame removably inserted in said pocket, complementary screw members arranged in said pocket and on said frame and engageable with each other for holding the frame in the pocket, a folding gate operatively connected to said frame and adapted to be foldingly received in said pocket, a bottom track pivotally connected to said frame and adapted to be swung upwardly across the opening in the pocket when the gate is in folded position, a hinged plate for closing the opening to said pocket, and a reinforcing member arranged at the top of the gate and movable with the gate for preventing side-sway of said gate when in extended position.
- 15 3. A folding gate comprising a plurality of vertical members pivotally connected together, a flat, flexible horizontally positioned continuous steel reinforcing member connected to one of the vertical members at the top thereof and slidable relative to other of said vertical members, a second foldable gate of like construction and having abutting relationship with the first gate when both of said gates are in extended position, and a pivoted bar connected to the first gate and slidably engaging the second gate to brace both of said gates when in extended position.
- 20 4. The combination of a wall having a pocket therein, a folding gate receivable in said pocket and comprising a plurality of vertical bars pivotally connected together, a member fixed to one of said vertical bars
- 25 and slidable relative to other of said bars whereby the gate is reinforced to prevent side-sway thereof when in extended position, said reinforcing member being movable inwardly and outwardly and adapted to extend down into said pocket when the gate is moved to folded position, and a curved member arranged in said pocket and acting as a guide for said reinforcing member.
- 30 5. A foldable gate comprising a plurality of vertical bars, diagonal lattice bars pivoted to the vertical bars, said vertical bars being provided with horizontal slots at their upper ends, a continuous single flat flexible horizontally positioned steel member arranged in said slots and fixed to one of said bars and acting as a reinforcing member for said gate to prevent side-sway thereof, a floor track, and rollers running on said track and carrying the gate, and means at one side of the

gate for guiding the steel member during folding movement of the gate.

In witness whereof, I have hereunto subscribed my name.

MICHAEL MARTINEK.
